ARTHUR H. BEDWORTH, OF EVERETT, MASSACHUSETTS, ASSIGNOR TO SPECIALTY AUTOMATIC MACHINE COMPANY, OF CHELSEA, MASSACHUSETTS, A CORPORATION OF MASSACHUSETTS

PAPER CONTAINER

Application filed June 23, 1931. Serial No. 546,252.

This invention relates to paper containers, and has particular reference to such paper articles as are employed for holding material which, either wholly or partly, is of such liquid nature as to require closures, especially the bottoms, that will not permit the contents to leak out.

While the invention is illustrated as at the bottom of a round or cylindrical container, it is to be understood that I do not limit myself thereto as the same structure could be utilized for the tops of paper containers, or even for the ends of containers which are other than round in cross section.

Heretofore, so far as I am aware, paper cups or bottles or other paper containers, especially of cylindrical form, are not reliably leak-proof because, owing to the various methods of making and the variations in the manufacture of paper, it is almost impossible to make a leak-proof container because of difficulty in having the various closely fitting portions formed together under pressure so that said portions will conform to each other closely and tightly.

The object of my present invention is to provide paper containers with end closures the margins of which are so convoluted in an inter-engaged and compressed manner as to effectually prevent leakage at any point of said margins.

With said object in view, my invention consists in the containers having end closures constructed substantially as hereinafter described and claimed.

Of the accompanying drawing which is on a considerably enlarged scale in order to clearly illustrate the different members of the container,

Figure 1 is a side elevation, partly broken out or in section, of the bottom portion of a container in its first condition or step of construction.

Figures 2, 3 and 4 are similar views, illustrating successive steps of construction, the last of said figures illustrating the finished structure.

Similar reference characters indicate similar parts or features in all of the views.

Referring first to Figure 1, the cylindrical

or tubular body member *a* has inserted a short distance within one end thereof, a disk *b* having a marginal flange *c*. If and when any adhesive is employed as hereinafter described, such adhesive may be either applied to the flange *c* or to the inner surface of the lower portion of the body member *a* before the disk *b* is located in the position illustrated in said Figure 1. I do not find it essential, however, to employ any adhesive, because the subsequent operations to be described produce a bead having such interlocked and compressed members as to very effectively prevent the existence of any crevices through which any liquid can pass.

The next step in the construction of the container is to turn the edge portion *d* of the body *a* inward and up inside the flange *c* as illustrated by Figure 2, and then a second or outer disk *e* which has been previously formed with a marginal flange *f* is inserted close to the disk *b* with its flange *f* fitting closely inside the edge of the in-turned portion *d* of the body, to bind said edge as illustrated by Figure 3.

Finally, by any suitable crimping mechanism, all of the portions which extend below the edge of the flange *f* are turned inwardly and compressed inside said flange *f*, said flange and also the layers of material outside said flange being also subjected to compression to ensure the several layers remaining in the triple-thick condition illustrated by Figure 4. This beading operation effects such interlocking of portions of the two disks and the body member that an effective tight seal is obtained without employing any adhesive.

If adhesive is desired, suitable glue will be preferably applied around the interior of the body member *a* over such area thereof that when the body portion *d* is turned in to the position shown in Figure 2, both sides or surfaces of the disk flange *c* will be adhesively connected. Of course glue can be applied elsewhere if desired.

By the structure illustrated and described, the following advantages are obtained:

A perfect leak-proof closure is obtained with a minimum amount of wastage. And

under actual construction the paper lends itself to a tight crimping which is necessary to make a leak-proof closure at a minimum cost of manufacturing operations. From Figure 4, it will be understood that a bottom closure produced as described, will prevent leakage because, in order for any contents to leak or seep through, such contents would have to travel through an extensive path, and such path is tightly formed or compressed. This advantage results mainly from the important feature that both of the flanges of the two disks *b* and *e* are rolled or crimped within a portion of the body of the container, and are compressed therein. Another way of explaining the advantage over any paper container known to me is that the marginal flanges of the inner and outer disks *b* and *e* being enclosed by a portion *d* of the body *a*, provides a triple-thick rim or bead at the bottom of the container.

Having now described my invention, I claim:

1. A paper container having an end closure comprising inner and outer disks, the inner disk having a marginal flange enclosed by a portion of the body of the container and providing a triple-thick rim, and the outer disk having a marginal portion enclosed by the said triple-thick rim.
2. A paper container comprising a body having an inwardly-turned end portion, a disk having a marginal flange enclosed in said inwardly-turned portion of the body, and a second disk having a marginal flange, the said inwardly-turned portion of the body and the disk flange that is enclosed therein being crimped over the flange of the said second disk.
3. A paper container comprising a body member having an end closure consisting of two disks each having an outwardly turned marginal flange, the flange of the inner disk being enclosed in an inwardly turned portion of the body member, and the flange of the outer disk bearing against the edge of said inwardly turned portion of the body member, the said inwardly turned portion of the body member and the inner disk flange which is enclosed thereby being rolled inwardly and locking the flange of the outer disk in position.

In testimony whereof I have affixed my signature.

ARTHUR H. BEDWORTH.
